[57] CLAIM

The ornamental design for a wireless telephone base
station, and described.

DESCRIPTION

FIG. 1 is a top plan view of the wireless telephone base
station, showing my new design;

FIG. 2 is an elevational view of the front side of the
wireless telephone base station;

FIG. 3 is an elevational view of one end of the wireless
telephone base station;

FIG. 4 is an elevational view of the other end thereof;

FIG. 5 is an elevational view of the rear side of the
wireless telephone base station; and

FIG. 6 is a bottom plan view thereof.

*Fig. 1.**Fig. 2.**Fig. 3.**Fig. 4.**Fig. 5.**Fig. 6.*
